United States Patent Office

Des. 209,313
Patented Nov. 21, 1967

209,313

COASTER

Mei Appel, Livingston, and Martin Schnur, West Orange,
N.J., assignors to Elpo Industries Inc., Fair Lawn, N.J., a corporation of New Jersey

Filed Feb. 8, 1967, Ser. No. 5,721

Term of patent 14 years

(Cl. D44—10)

FIG. 1

FIG. 2

We claim:

The ornamental design for a coaster, as shown and described.
